Primary Examiner—Susan J. Lucas

[57] CLAIM

The ornamental design for a communication handset, as shown and described.

DESCRIPTION

FIG. 1 is a top plan view showing the communication handset of my claimed design, where the opposite side is a mirror image thereof including the lower portion of FIG. 2;

FIG. 2 is a view in side elevation of my claimed design, looking from right to left on FIG. 1;

FIG. 3 is a view in end elevation of my claimed design as taken along line 3—3 of FIG. 1; and,

FIG. 4 is a view in end elevation of my claimed design as taken along line 4—4 of FIG. 1.
